CLAIM

We claim the ornamental design for a water module for above-ground swimming pools, as shown and described.

DESCRIPTION

FIG. 1 is a front perspective view of a water module; FIG. 2 is a back perspective view of the water module shown in FIG. 1;

FIG. 3 is a front elevation view of the water module shown in FIG. 1;

FIG. 4 is a rear elevation view of the water module shown in FIG. 1;

FIG. 5 is left-side elevation view of the water module shown in FIG. 1;

FIG. 6 is right-side elevation view of the water module shown in FIG. 1;

FIG. 7 is a top plan view of the water module shown in FIG. 1; and,

FIG. 8 is a bottom plan view of the water module shown in FIG. 1.

The portions shown in stippled lines do not form part of the design.

1 Claim, 7 Drawing Sheets
